UNITED STATES PATENT OFFICE.

CHARLES T. WITTSTEIN, OF NEWARK, NEW JERSEY.

JEWELER'S TAG.

857,778.

Specification of Letters Patent.

Patented June 25, 1907.

Application filed August 1, 1906. Serial No. 328,666.

To all whom it may concern:

Be it known that I, CHARLES T. WITTSTEIN, a citizen of the United States, residing at Newark, in the county of Essex and State of New Jersey, have invented certain new and useful Improvements in Jewelers' Tags, of which the following is a specification.

This invention relates more particularly to tags for marking finger rings, although it will be seen that it is equally adapted to similar articles such as bracelets and the like, or may if desired, be used for any other articles to which it could be applied.

The objects of this invention are to secure a compact tag which can be securely and firmly attached to the article, and lie close to the same, being in a large measure fixed with relation thereto; to enable the entire outer surface of the tag to be utilized for printing; and thus secure the maximum amount of space for advertising or marking purposes; to enable the tag to be easily and quickly applied to an article, by simple operation; to save cost and labor in manufacture, and to obtain such other advantages and results as may be brought out in the following description.

Referring to the accompanying drawings in which like numerals of reference indicate corresponding parts in each of the several figures, Figure 1 is a plan view of the outside of my improved tag in extended position, and Fig. 2 is a similar view of the inner side or surface; Fig. 3 is an edge view of the tag as its two end portions are being brought together in applying it to an article, and Fig. 4 is a similar view after said end portions have been pressed together; Figs. 5 and 6 show in side and edge view, respectively, a ring having my improved tag applied thereto.

In said drawings, the body portion of my improved tag is shown as comprising a dumb-bell shaped piece of parchment or other suitable material, 1, 1, indicating the enlarged end portions thereof, and 2, a narrower neck or connecting strip joining the two end portions. At one side of the said body portion as extended, the ends 1, 1, are made adhesive as by a coating 3 of gum or other mucilaginous matter, the middle portion or neck 2 being non-adhesive or devoid of such gum or mucilage. The said end portions 1, 1, are each laterally widened or extended adjacent to the neck or connecting strip 2, but are of the same size and shape as each other so as

to coincide at their edges when folded together to form the display portion or tab. This display tab is thus wider and larger than the attaching portion of the tag when applied to an article, so that even though doubled or 60 pressed by use back against the attaching portion, its marked face or side will not be appreciably obscured or concealed.

In use, one end of the body of the tag is thrust through the ring or other article until the neck 2 lies across the band of the ring and then the two end portions 1, 1, are moistened and pressed firmly together at their adhesive faces, as clearly illustrated in Figs. 3 and 4 of the drawings. Obviously this operation is 70 extremely simple and easy to perform, only a pinch of the thumb and fore-finger being needed. The end portions of the tag are not only adhesive because of the coating of gum or cement; while the connecting portion is 75 non-adhesive, but the layer of gum or cement on said end portions furthermore stiffens them with respect to the middle or connecting portion, so that under pressure at its ends the point of bending of the tag is pre-determined or located at said uncoated or exposed middle portion of the flexible body part, and this occurs automatically or without any special care or attention on the part of the user. The end portions 1, 1, become practically a single piece, and the neck or middle strip 2, forms a loop around the article. This loop, because narrow and devoid of cement or glue, is flexible, while the body portion or display tab of the applied tag is, because of its double thickness and the layers of cementitious matter between, decidedly stiff and strong in comparison. The result of this is that any force or pressure tending to double or crumple the display tab will be 90 resisted by it and taken up by the slender flexible attaching portion or neck.

Preferably the said neck or connecting strip 2 is of such length that it closely encircles the band of the ring when the two end portions are gummed together, or in other words fits thereon with sufficient frictional engagement to hold the tag in any desired position to which it may be turned. This secures a firm and fixed relation of the tag to 105 the article, as compared to the looseness of the ordinary tag when tied to a ring with a piece of cord; the tag is therefore not flying all around, to the great detriment of appearance and great inconvenience in handling. 110

The tag is preferably swung to lie in the plane of the ring and be encircled thereby as shown in Figs. 5 and 6, so that it is entirely out of the way while yet perfectly convenient for inspection, and the ring can be inserted in the velvet crevice of a box or tray without any attention whatever to the tag and so as to completely conceal the same.

Aside from the ease with which my improved tag is applied, it should be noted that the entire outer surface of the same is available for marking or advertising purposes, there being no holes, cords or clamps, or overlapping ends, to obstruct the surface. Maximum space can thus be utilized, and consequently the size of the tag reduced without curtailing its comparative capacity. Furthermore it should be noted that to secure the printing upon both the opposite sides of my improved tag as the same is upon an article of jewelry, it is not necessary to pass the tag twice through the printing press, but by having the tag in extended position as shown in Fig. 1, the printing can all be done at a single impression, thus saving much time and labor.

Having thus described the invention what I claim as new is:

As an article of manufacture, a jewelers' tag comprising a piece of flexible material having a middle connecting portion adapted to bend around a body to which the tag is to be applied and opposite end portions adapted to be brought flatwise together by such bending and form a display tab, one side surface of said piece of flexible material being provided with a layer of cementitious matter at the said end portions thereof and devoid of the same at the said middle connecting portion, whereby said end portions may be joined into said display tab and are furthermore stiffened with respect to the middle connecting portion for the purposes set forth, and the other side of said piece of flexible material being adapted at the end portions thereof to constitute the outer exposed faces of the said display tab.

CHARLES T. WITTSTEIN.
